Primary Examiner—Antoine Duval Davis
Attorney, Agent, or Firm—Kenneth A. Roddy[57] **CLAIM**

The ornamental design for a mold for forming concrete border stones, as shown and described.

DESCRIPTION

FIG. 1 is a perspective view of a mold for forming concrete border stones showing my new design from the top, one end, and one side, the opposite side and end being a mirror image of that shown;

FIG. 2 is a top plan view thereof;

FIG. 3 is a side elevation view thereof;

FIG. 4 is an end elevation view thereof;

FIG. 5 is a bottom plan view thereof;

FIG. 6 is a longitudinal cross section thereof taken along line 6—6 of FIG. 1; and,

FIG. 7 is a transverse cross section thereof taken along line 7—7 of FIG. 1.
